United States Patent Office

Des. 229,535
Patented Dec. 11, 1973

229,535

HALF-ROUND FLAT, HOLLOW FILE

Elwin Theobald, 4631 Solano Way,
Fair Oaks, Calif. 95628

Filed Dec. 2, 1971, Ser. No. 204,392

Term of patent 14 years

Int. Cl. D8—05

U.S. Cl. D8—90

FIG. 1

FIG. 2

FIG. 3

FIG. 4

FIG. 5

FIG. 6

FIG. 1 is a perspective view from the top of the file showing my new design;

FIG. 2 is a side elevational view thereof;

FIG. 3 is an exploded perspective view thereof;

FIG. 4 is a top plan view thereof;

FIG. 5 is an end elevational view, the opposite end having the same appearance, and

FIG. 6 is a bottom plan view of the file.

The toothed configuration shown representatively in FIGS. 1 and 3 is continuous across the upper and lower surfaces.

I claim:

The ornamental design for a half-round flat, hollow file, as shown and described.
